Fig. 3

Fig. 4

Fig. 5

Fig. 6

Fig. 7

Fig. 8

FIG. 2 is a top plan view thereof;

FIG. 3 is a front elevational view thereof;

FIG. 4 is an elevational view taken from one side thereof;

FIG. 5 is a rear elevational view thereof;

FIG. 6 is an elevational view taken from the side opposite that shown in FIGURE 4;

FIG. 7 is a cross-sectional view taken on the line 7-7 of FIG. 2; and

FIG. 8 is a bottom plan view thereof.

We claim:

The ornamental design for an O ring display case, as shown.
